UNITED STATES PATENT OFFICE.

JOHN ROLLIN ANSTETH, OF BUFFALO, NEW YORK.

DESIGN FOR A CLOCK-CASE.

SPECIFICATION forming part of Design No. 37,456, dated June 6, 1905.

Application filed March 17, 1905. Serial No. 250,686. Term of patent 7 years.

To all whom it may concern:

Be it known that I, JOHN ROLLIN ANSTETH, a citizen of the United States, residing at Buffalo, in the county of Erie and State of New York, have invented a new, original, and ornamental Design for a Clock-Case, of which the following is a specification.

In the accompanying drawings, Figure 1 is a perspective view of a clock-case, illus-

trating the design; and Fig. 2 is a side elevation thereof.

What I claim is—

The ornamental design for a clock-case, as shown.

JOHN ROLLIN ANSTETH.
